(57) **CLAIM**

The new design for a container for aroma therapy oils, as shown and described herein.

DESCRIPTION

FIG. 1 is a front elevation view of a container for aroma therapy oils showing my new design;

FIG. 2 is a left side elevation view thereof;

FIG. 3 is a right side elevation view thereof;

FIG. 4 is a rear elevation view thereof;

FIG. 5 is a top plan view thereof;

FIG. 6 is a bottom plan view thereof;

FIG. 7 is a front elevation view of a container for aroma therapy oils shown with the cap removed for clarity of illustration;

FIG. 8 is a left side elevation view thereof;

FIG. 9 is a right side elevation view thereof;

FIG. 10 is a rear elevation view thereof;

FIG. 11 is a top plan view thereof; and,

FIG. 12 is a bottom plan view thereof.
